LOCK STRUCTURE

Walter R. Schlage, San Francisco, Calif., assignor
to Schlage Lock Company, San Francisco,
Calif., a corporation of California

Application January 10, 1934, Serial No. 706,049

8 Claims. (Cl. 70—16)

This invention relates to a lock structure of the type shown in my co-pending application entitled "Door lock", filed June 14, 1932, Serial Number 617,117, and particularly to improvements in the 5 construction and mounting of the latch bolt retractor and cooperating mechanism.

The object of the present invention is to generally improve and simplify the construction and 10 operation of latch structures of the character described; to improve the construction of the latch bolt retractor; to provide a rigid guide and supporting plate for the latch bolt retractor; and further, to provide a yielding latch for securing or releasing the dogging member whereby certain 15 parts of the lock structure are rendered inoperative.

The invention is shown by way of illustration in the accompanying drawings, in which—

Fig. 1 is a horizontal section of the lock structure showing it inserted in a door, said view also 20 showing the dogging mechanism in released position.

Fig. 2 is a view similar to Fig. 1 but showing the dogging member in dogging position.

Fig. 3 is a vertical section taken at right angles to Fig. 1.

Fig. 4 is a cross section in side elevation taken on line IV—IV of Fig. 3.

Fig. 5 is a perspective view of the push rod and 30 button whereby dogging mechanism is actuated.

Fig. 6 is a perspective view of one of the spindles.

Fig. 7 is a perspective view of the latch bolt retractor guide.

Fig. 8 is a perspective view of one of the housing sections.

Fig. 9 is a perspective view of the lock housing cover.

Fig. 10 is a perspective view of the latch bolt 40 retractor.

Fig. 11 is a perspective view of the auxiliary retractor.

Fig. 12 is a perspective view of the dog latch.

Fig. 13 is a perspective view of the dog latch 45 showing it in a different position from that shown in Fig. 12.

Fig. 14 is a perspective view of the dogging member.

Fig. 15 is a perspective view of one of the 50 housing sections.

Referring to the drawings in detail, and particularly Figs. 1 to 4, inclusive, A indicates a door in which is inserted a latch actuating unit generally indicated at B and a latch unit generally indicated at C. The units are separately

insertable in the door and the door has two openings formed therein; one opening 2 which is bored through opposite faces of the door to receive the latch actuating unit B, and a second opening which is drilled through the edge of the door, as indicated at 3, to receive the latch unit C. The manner in which the units are secured in the respective openings will be hereinafter described.

The latch actuating unit consists of a central housing from opposite ends of which extend hub 10 members 4 and 5. The hub member 4 carries one part of the housing and the hub member 5 the second part of the housing. The part of the housing carried by the hub member 4 consists of an end plate 6 on which is formed a pair of 15 horizontally disposed bracket arms 7 and 8, see Fig. 8. These bracket arms are cast or formed integral with the plate 6 and they are provided with a pair of outwardly extending threaded lugs 9—9 to receive securing bolts 10—10 which will 20 hereinafter be referred to. The bracket arms are also provided with a pair of hook-shaped lugs 11 and 12 and the arms are further provided with lugs 13 and with aligned slots 14. The part of the housing carried by the hub member 5 terminates in a substantially circular plate 15. This is provided with upper and lower pairs of rectangular shaped openings 16 and 17 to receive the lugs 11 and 12 and the plate 15 is also provided with openings 18 which align with the 25 threaded lugs 9—9, which, as previously stated, are provided for the purpose of receiving the securing bolts 10—10.

The housing is assembled by placing the plate 15 against the face of the bracket arms 7 and 35 8 in such a position that the lugs 11 and 12 will pass through the slotted openings 16 and 17. A cover housing 19, see Fig. 9, is slipped over the housing sections as clearly shown in Figs. 1 to 3. The end of the cover housing is provided with 40 slots 16a and 17a for the lugs 11 and 12 to pass through and one of the lugs is perforated, as shown at 20, to receive a cotter pin, or the like, so as to secure the several parts of the housing against separation when assembled. The housing, when so assembled, may be inserted in the opening 2 of the door. The hub member 4 is externally threaded, as shown in Figs. 1 and 2, and it carries an escutcheon plate 21. This plate is screwed inwardly or outwardly on the threaded 45 section of the hub until the housing assumes a central position with the opening 2 of the door. An escutcheon plate 22 is then slipped over the end of the spindle 5 and the bolts 10—10 are then passed through the escutcheon plate 22 and 50

through the openings 18 which align with the threaded lugs 9. These lugs function as nuts and when the bolts 10 are tightened the escutcheon plates will securely grip the opposite faces of the door and the housing will be rigidly secured. Previous to the installation just described, it will be understood that a retracting mechanism will be inserted in the housing and also that spindles will be inserted, such as shown at 24 and 25, 10 and thereafter knobs such as shown at 26 and 27.

The retracting mechanism just referred to is supported by the housing section indicated by the numerals 4, 6, 7 and 8, see Fig. 8. The mechanism consists of a guide plate, see Fig. 7, 15 consisting of a pair of horizontal arms 30 connected at one end by a cross bar 31. The forward ends of the guide bars terminate in ears or lugs 32. These are adapted to be received by the slotted sections 14 of the bracket arms 20 7 and 8, while the opposite ends of the guide arms 30 are received between the lugs 13, there being two lugs on the bracket arm 8 and two lugs on the bracket arm 7. The slots 14 and the lugs 13 secure the guide member centrally between the 25 plates 6 and 15 of the housing and the guide plate forms a guide and support for the latch bolt retractor which is clearly shown in perspective in Fig. 10. The retractor consists of a pair of horizontal arms 33 which are provided with upper and lower shoulders 34, these shoulders 30 being formed on opposite sides of the arms. The arms are longitudinally slotted, as shown at 35, and the arms are connected by an end plate 36 through which is formed a central opening 37. 35 The forward ends of the arms terminate in fingers 38 and they are provided to engage the lugs 39 formed on the rear end of a latch bolt retractor bar 40, see Fig. 4.

By referring to Fig. 11 it will be noted that an 40 auxiliary retractor is shown. This is nothing but an end plate 41 provided with two slotted rearwardly extending arms 42. The function of the auxiliary retractor will hereinafter be described.

45 In assembling the mechanism shown in Figs. 7, 8, 10 and 11, the auxiliary retractor is first placed within the arms of the retractor and the two retractors are then slid endwise over the guide member shown in Fig. 7, this being readily 50 accomplished as the arms 33 of the retractor are longitudinally slotted to receive the arms 30 of the guide member. When the two retractors have been placed on the arms of the guide member, the guide member will be inserted endwise 55 between the bracket arms 7 and 8 so that the rear ends of the arms will engage between the lugs 13 and the lugs 32 on the forward ends of the arms will engage in the notches or slots 14 of the bracket arms 7 and 8. When so inserted, 60 plate 15 is applied over the lugs 11 and 12, as previously described, and after this is accomplished the cover housing 19 is applied and is secured in position by a cotter pin passing through the perforation 20 of one of the lugs 65 12. The housing, thus assembled, carries the guide member shown in Fig. 7, together with the retractors shown in Figs. 10 and 11, and as the housing cover 19 encloses the mechanism, endwise movement of the guide member shown in 70 Fig. 7 from between the slots and lugs supporting the same is prevented; this being clearly shown in Fig. 4. Each housing section of the hub members 4 and 5 carries a spindle such as shown in Fig. 6. One spindle is numbered 24 75 and passes through the hub section 4, the other

spindle is numbered 25 and it passes through the hub section 5. Each spindle is provided with a rollback member such as shown at 43, see Fig. 6, and these rollback members engage the shoulders 34 formed on the retractor. The spindles are 5 first inserted in the respective housing sections, when these are being assembled, and the guide plate having the retractors mounted thereon are then inserted between the bracket arms 7 and 8. Plate 15 carrying the hub 5 is then applied and thereafter the housing cover, and when the mechanism is so assembled, it is ready for insertion in the opening 2 of the door where it is inserted, as previously described, by the application of the escutcheon plates and the tightening of the bolts 10-10.

In the actual installation of a lock of this character in a door, the latch unit section C is first inserted. The latch actuating unit is then inserted through the opening 2 and when it is 20 inserted an interlock is formed between the two sections, which need not be here described as it has been fully disclosed and covered in a number of patents already issued to me. Suffice it to say, that when the lock mechanism is 25 completely installed, it is only necessary to rotate one knob or the other to open the door. In rotating the knob a cooperating spindle is rotated and as each spindle carries a rollback member 43, this rollback will engage the shoulders 34 30 of the retractor and cause it to slide inwardly on the guide arms 30, and as the retractor slides inwardly the fingers 38 engage the lugs 39 on the latch bolt retractor bar 40 and thus pulls the latch bolt inwardly and frees it with relation to the striker plate and the door frame. The latch bolt is projected by means of a spring 45 so that whenever a knob is released, after retraction, the latch bolt will be automatically projected and the knob will return to normal position.

In lock structures of this character it is common to employ a push button 46 in the inner knob. This push button actuates a dogging mechanism and the dogging mechanism functions to dog the outer spindle and knob against rotation, thereby preventing opening of the door from the outside when the push button 46 has been depressed. This mechanism has been fully 50 described in a number of my patents so a brief description should suffice. The push button carries a pusher rod 47, see Figs. 1 to 3, and also Fig. 5. On the end of the rod opposite the push button 46 is mounted two cone-shaped collars 48 and 49. The outermost collar 48 engages one end of 55 a spool-shaped member 50, see Figs. 1 to 3, and also Fig. 14. This spool-shaped member carries a dog 51 which is the actual dogging member. The spool-shaped member is guided and 60 slidably mounted in the inner end of the spindle 24. The inner end of this spindle is slotted as shown at 52, see Figs. 1, 2 and 6, and the inner end of the hub member 4 is similarly slotted, as shown at 53. When the push button and pusher rod assumes the position shown in Fig. 1, the 65 dogging member is clear with relation to the slot 52 on the inner end of the spindle 24, but when the push button is depressed, as shown in Fig. 2, dogging member 51 will not only enter the slot 53 but also the slot 52 of the spindle 24 70 and as the hub member 4 is non-rotatable and as the dogging member passes both through the slot 52 and the slot 53 spindle 24, together with the outer knob 26, will be dogged against rotation and the door cannot be opened from the 75

outside when the push button has been depressed.

In moving the dogging member to dogging position it is necessary to secure the push button, the pusher rod, and the dogging member in the dogging position, and that is the function of the inner collar 49 on the pusher rod. That is, a latch cooperates therewith and engages collar 49 when the button has been depressed and the dogging member assumes dogging position. This latch is, however, releasable either by rotation of the inner knob or by depression of the latch bolt indicated at 60, the depression of the latch bolt 60 being accomplished by manual depression or by slamming or closing of the door. In either instance the latch securing the dogging member in dogging position will be released so that it will not be possible for a person leaving a room to lock him or herself out. For instance, a person leaving the room might inadvertently or carelessly depress the button and thereby throw the dogging member into dogging position, but the moment he or she closes the door, latch bolt 60 will be depressed and that will release the dogging member.

The latch cooperating with the collar 49 is best shown in Figs. 1, 2, 12 and 13. It consists of a flat plate 61 which is seated in the opening 37 formed in the end of the retractor, see Fig. 10. A spring 62 is interposed between the cross arm 31 of the guide member and the plate 61 so that the plate 61 is yieldingly held in the opening 37 of the retractor. The inner face of the plate 61 is provided with a small protuberance in the form of a latch which is indicated at 63. Its function will be as follows: If the push button is pushed inwardly from the position shown in Fig. 1, the cone-shaped collar 49 will engage the inclined face of the latch 62 and thereby push the plate 61 inwardly against the tension of the spring 62. The moment the push button has been fully depressed, the collar 49 will assume the position shown in Fig. 2. That is, the collar will have passed slightly beyond the latch 63, thereby permitting spring 62 to return the plate 61 to normal position, or in other words to a position where the latch 63 will engage the outer face of the collar 49 and thereby latch or secure the push button and the pusher rod in depressed position. It also secures the dogging member in dogging position as this has been pushed into the slots 52 and 53, previously described. If it is desired to release the latch 63 so that the dogging mechanism may be rendered inoperative, it is only necessary to turn the inner knob or to depress the latch bolt 60. If the inner knob is rotated the rollback member on the inner end of the spindle will engage the shoulders 33 of the retractor and the retractor will be forced inwardly in the housing, thus moving the latch 63 away from the collar 49, and when it is released, springs 70 and 71 will return the dogging member and the pusher rod and the push button to normal position. Similarly, if latch bolt 60 is depressed either manually or by closing of the door, the latch bolt bar 40, see Fig. 4, will move inwardly, the lugs 39 on the inner end will then engage the end plate 41 of the auxiliary retractor and as this is mounted within the main retractor and moves in unison therewith the main retractor will again be moved inwardly thus releasing the latch 63 and permitting the parts held thereby to return to normal inoperative position.

A latch for securing the push button and dogging means actuated thereby in dogging position has previously been employed by me, and is dis-

closed in several of my patents, but, in each instance, the latch depends upon the tension of the spring 45 of the latch bolt to hold it in latching position. The tension of this spring is considerable, hence whenever the push button was depressed and the latch engaged, it would engage with a click; also it required an unnecessary amount of endwise pressure on the end of the push button to press it into dogging position. In the present instance spring 45 is entirely eliminated as far as the action of the latch 63 is concerned. The spring 62 is the only spring which holds latch 63 in latching position, and as this can be a soft yielding spring, that will be the only resistance to the operation of the latch 63, and latch 63 can thus be softly and yieldingly supported and will accordingly be almost noiseless in operation. This is a desirable feature under many circumstances, for instance if a small child has just been put to sleep in the bedroom and the mother or nurse desires to remain in the room and yet exclude others from entering, she can step over to the door and push the button into dogging position without any click or noise. That could not be accomplished with any of the structures shown in my previous applications and to that extent was objectionable, but the structure here disclosed entirely overcomes this objection.

The novel features of this application are the latch 63, the plate 61 supporting the same, and the spring 62 cooperating therewith. The other novel features are the provision of the auxiliary retractor 41, the construction of the main retractor shown in Fig. 10, the construction of the guide member shown in Fig. 7, and the construction of the housing section shown in Fig. 8 to receive the guide member and retractors. These are the only novel features as all the remaining mechanism has been fully disclosed in other issued patents and copending applications.

Having thus described my invention, what I claim and desire to secure by Letters Patent is:—

1. In a lock structure a pair of hub members, a housing forming a part of the hub members and spacing the hub members apart, a guide plate composed of a pair of spaced arms secured substantially centrally of the housing, a latch bolt retractor slidably mounted on said arms, said latch bolt retractor being composed of a pair of spaced arms each longitudinally slotted to receive the guide arms, and an end plate connecting the spaced arms of the retractor.

2. In a lock structure a pair of hub members, a housing forming a part of the hub members and spacing the hub members apart, a guide member insertable in the housing, a latch bolt retractor slidably mounted on the guide member, and a cover housing surrounding the first-named housing and securing the guide member and retractor against removal from the first-named housing.

3. In a lock structure a housing, a main retractor in the housing, a latch bolt, means forming a connection between the main retractor and the latch bolt whereby movement is transmitted to the latch bolt in one direction only, and an auxiliary retractor carried by the main retractor, said auxiliary retractor adapted to impart movement to the latch bolt in the opposite direction and said auxiliary retractor adapted to impart movement to the main retractor upon depression of the latch bolt.

4. In a lock structure a housing member comprising a hub having an end plate, a pair of spaced parallel arms carried by said plate, a guide plate

insertable between the arms, a pair of spaced lugs at one end of each arm to receive one end of the guide plate, and a pair of lugs on the guide plate insertable in slots formed on opposite ends of the arms to secure that end of the guide plate.

5. In a lock structure a latch bolt retractor guide comprising a pair of spaced arms connected at one end by a cross arm and an outwardly projecting lug formed on the outer surface and on the opposite end of each arm.

10. In a lock structure a latch bolt retractor comprising a pair of flat spaced parallel arms connected at one end by a cross arm and said flat parallel arms being centrally slotted from end to end to receive a guide plate.

15. In a lock structure a latch bolt retractor comprising a pair of flat spaced parallel arms connected at one end by a cross arm and said flat

parallel arms being centrally slotted from end to end to receive a guide plate, and each flat arm being reduced in width for a portion of their length to form shoulders on each side thereof to be engaged by rollback members.

5

8. In a lock structure a housing carrying a retractor, a housing carrying a latch bolt, a retractor bar connected at one end with a latch bolt, a pair of lugs on the inner end of the retractor bar, a pair of fingers on the retractor engageable with the lugs to retract the retractor bar and the latch bolt when the retractor is retracted, and an auxiliary retractor insertable in the first-named retractor, said auxiliary retractor adapted to be engaged by the inner end of the retractor bar when the latch bolt is depressed so as to impart movement to the auxiliary retractor and the retractor when the latch bolt is depressed.
